(Cl. D34—5)

To all whom it may concern:

Be it known that we, Robert I. Anderson and Bert Hoeker, both citizens of the United States, residents, respectively, of Grand Haven, in the county of Ottawa, State of Michigan, and of Muskegon, in the county of Muskegon, State of Michigan, have jointly invented a new, original, and ornamental Design for a Masking Unit for Bowling Alley Pin Setters or the Like, of which the following is a specification, reference being had to the accompanying drawings, forming a part thereof.

Fig. 1 is a front elevation of a masking unit for bowling alley pin setters or the like, showing our new design.

Fig. 2 is a plan view thereof.

Fig. 3 is a side elevation thereof.

We claim:

The ornamental design for a masking unit for bowling alley pin setters or the like, as shown.

ROBERT I. ANDERSON.
BERT HOEKER.
